UNITED STATES PATENT OFFICE.

WINFIELD HANCOCK YOST, OF MONTREAL, QUEBEC, CANADA.

CAR SIDE CONSTRUCTION.

1,267,834.

Patented May 28, 1918.

Application filed January 21, 1914. Serial No. 813,431.

To all whom it may concern:

Be it known that I, WINFIELD HANCOCK Yost, a citizen of the United States, and resident of the city of Montreal, Province of Quebec, Canada, have invented certain new and useful Improvements in Car Side Construction; and I do hereby declare that the following is a full, clear, and exact description of the same.

10 This invention relates to "ballast" cars or cars which are preferably constructed with open ends and adapted to have their contents discharged through the sides by means of a plow, the invention appertaining particularly to the construction of the car sides.

15 In plowing off cars of this type the side stakes obstruct a considerable quantity of the material being discharged, which obstructed material becomes so tightly packed between the stakes and plow as the latter moves forward, that a pressure is established which the stakes are unable to withstand and they are consequently forced outwardly and broken away from the car. Up to the 20 time of the present invention it has been proposed to avoid this damage and at the same time maintain adequate guides for the plow throughout the length of the car by the use, in place of certain of the ordinary 25 stakes, stub stakes or stakes of reduced height.

30 An object of the present invention is to avoid damage to the car by providing car sides which are so constructed as to be capable of yielding, without injury, under the pressure set up by the plow and thereby avoid the setting up of a damaging pressure between the car sides and the plow.

35 When a plow is passed through a car of ordinary construction spaces are presented between the practically vertical sides of the car and the inclined sides of the plow and it has been found that when one side only of the car is opened to discharge the material, 40 boulders and the like instead of being discharged frequently lodge in the space between the plow and the closed side of the car, with the result that such boulders are jammed against the car side and damage the 45 same.

50 The invention has for another object to avoid this damage by so constructing the car sides that they are adjustable and yieldingly maintain a position closely adjacent to the

55 plow irrespective of the position of the latter in the car and thus do away with the spaces at the sides of the plow.

Further objects and advantages will be hereinafter more fully described and particularly pointed out in the claims. 60

For full comprehension, however, of my invention reference must be had to the accompanying drawings forming a part of this specification in which similar reference characters indicate the same parts and wherein; 65

Fig. 1 is a transverse section of a car constructed according to my invention, the stake at the left of the figure illustrating a modified form;

Fig. 2 is a side elevation of a portion of 70 the car with parts broken away;

Fig. 3 is a horizontal section of a portion of the car side;

Fig. 4 is a detail section illustrating the position of the stakes and doors just as the 75 latter are released;

Fig. 5 is a view similar to Fig. 4 showing the stakes swung outwardly against the springs; and

Fig. 6 is a detail perspective view illustrating the connection of the spring-box with the stub stake. 80

The understructure of the car is of the approved construction including center sill 2, side sills 3 and cross-bearers 4 with the floor 85 5 thereon.

90 Each side of the car is of the usual construction inasmuch as it includes side stakes and top rails 6 supported by and extending between the tops of the stakes and having doors 7 hinged thereto as at 8.

Formerly the side stakes have been rigid, that is to say immovable with relation to the car and as a consequence have each constituted an abutment which, being unyielding, 95 causes the above described packing of the material therebetween and the plow until such a pressure is established that the stakes are broken or their connections with the car pulled away. To avoid this I provide stakes 100 9 which are connected to the car in a manner enabling the stakes to assume different positions with relation to the car, being preferably pivoted near the bottom to the car and permitted to swing laterally of the car 105 so that when the plow moves through the same and tends to pack the material against the stakes, the latter will yield and prevent

the tight packing of the material and the consequent damaging pressure upon the stakes.

It is necessary to provide guides for the plow at intervals along the car sides and for this reason I prefer to construct each stake in two parts including a stub stake 10 and the stake 9 which will then be pivoted to the stub stake. The lower end of the stub stake 10 is secured to the side sill 3 and extends up above the flooring a comparatively short distance to act as a plow guide, such stake being provided with a wear plate 10^a and pressed inwardly or recessed as at 10^b for the reception of such wear plate so that the latter will be flush with the sides of the stub stake and not interfere with the movement of the pivoted stake and also avoid the formation of an obstruction for the accumulation of material. The inner faces of both the pivoted stake and the stub stake are preferably beveled or curved in horizontal section so that the plow, if it happens to strike against the stakes, will work around and not catch upon the same and damage them. The stakes 9 may be of any suitable construction, those shown in the drawings being each of channel cross-section, disposed with its open side facing out from the car and inclosing the inner side margin of the stub stake. The inner face of the stub stake is beveled as at 11 and the pivoted stake cut away as at 12 to enable it to swing over the stub stake and out from the car, the beveled inner face 11 providing a flat bearing surface for the pivoted stake as shown at the left of Fig. 1 and in this position the stub stake provides an abutment for the support of the outwardly inclined pivoted stake. Curved members 9^c are secured to the sides of the pivoted stakes and form the curved or beveled inner face of the latter.

The outer edge of the lower portion of the stub stake may be provided with laterally extending flanges or stops 14 and the sides 15 of the stake 9, below the pivot point, may be located between these flanges and the side sill of the car, so that when the pivoted stake swings in either direction its lower end engages with and is braced by either the flanges or the side sill and its movement thereby limited. The flanges 14 are spaced a distance from the side sills to permit sufficient movement of the lower portions of the sides 15 to enable the pivoted stake to assume either an inwardly inclined position overhanging the car or a position inclined outwardly from the latter, while the opposite edges of the side portions 15 are preferably downwardly tapered so that they will bear flat against the stops formed by the flanges 14 and side sill 3, the inner tapered edge being laterally flanged as at 15^a.

As shown at the left of Fig. 1 the stub 65 stake flanges may be omitted and the lower

end of the pivoted stake rounded off. In this modified form the outward swinging of the stake is limited by its engagement with the beveled face 11 of the stub stake, while the inward swinging of such stake is limited by the engagement of the stake against the floor of the car, particularly the engagement of the lower ends of the stake members 9^c with the floor.

The support of the top rails and through them the doors, requires few stakes whereas plow guides are necessary at comparatively frequent intervals along the car sides and accordingly I prefer to utilize a reduced number of two-part or high stakes together with stub stakes 16 intermediate of the latter. The stub stakes, being of reduced height, only extend a short distance above the flooring 5 and thus permit the discharging material to freely pass thereover and through the car sides and it will therefore be seen that the stub stakes 10 and the intermediate stub stakes 16 provide adequate plow guiding means but are not of sufficient height to so obstruct the material as to set up a damaging pressure, while the pivoted stakes, by yielding as the material is pressed thereagainst, also avoid the setting up of a damaging pressure.

When plowing off a car the top rails are frequently damaged by rocks or lumps of material which are caught between the plow and top rails or forced up against the latter and to avoid this damage I have provided for a limited upward movement of the car sides including the top rails whereby under the pressure of the obstructions such top-rails will move up and so enable the obstructions to work thereunder and out of the car instead of damaging the top rails as heretofore, the top rails dropping to their normal position when the obstruction drops away. I secure this advantageous result by forming a pin and slot connection between the stub stake and stake 9. In the drawings the stub 110 stake is formed with a slot 10^d within which a pin 10^e carried by the stake 9, is located.

The stub stakes 10 are preferably of channel cross-section with their open side facing outwardly from the car and between each 115 stub stake and pivoted stake a spring 17 is located which yieldingly holds the pivoted stake against outward movement and normally maintains this stake in its inwardly inclined position overhanging the car floor- 120 ing. The spring 17 is contained in a box 17^a pivotally mounted between the sides 15 of the stake 9 preferably by means of pins 18 upon such sides and which enter slots 19 formed in the box 17^a. One end of the box 125 is open and the spring protrudes at this end and has a rounded bearing head 20 thereon, the opposite end of the box being closed and having one or more hooks 21 thereon and a lip 22 located above the hooks and curved 130

upwardly therefrom to form with the hooks a flared opening. Laterally extended flanges 20^a are also formed upon the box at its closed end.

5 The beveled inner face 11 of each stub stake is cut away at the top at 21^a and the upwardly extending sides formed by the cuts are notched on their inner edges to form shoulders 18^a. When the doors are closed 10 and the stakes 9 in their normal position overhanging the car flooring the boxes 17^a and hooks 21 are located between the upwardly extending sides of their respective stub stakes, with the flanges 20^a at the closed 15 ends of the spring boxes bearing against the shoulders 18^a of the stub stakes and the springs 17 expanded with their heads 20 bearing against the outer faces of the pivoted stakes.

20 A crank shaft 24 is located at the outer side of the doors at each side of the car and passes through slots formed by straps 25 secured to the doors. The offset portions 26 of the shafts inclose the spring boxes, being 25 located within the hooks 21 and adjacent to the closed ends of the boxes and in this position the doors are held against inward or outward movement while the pivoted stakes have a movement against the resistance of 30 the springs, limited by the engagement of the stakes with the open ends of the boxes 17^a. To hold the doors more securely fastened the crank shafts may, if desired, be offset at 14^a adjacent to the stub stakes 14^a 35 and the latter formed with shoulders 14^a against which the offset portions 14^a are adapted to bear.

The crank shafts are adapted to be swung up to release the doors and to facilitate the 40 opening of the doors the offset portions 26 are preferably inclined as shown at the right of Fig. 1. The locking position of the shafts is maintained by pawls or cams 27 which are pivoted to the doors above the shafts and 45 are adapted to be swung into engagement with the latter, which may be inwardly offset as at 28 for this purpose.

When a plow is to be passed through the car, the cams 27 are swung out of engagement with the crank shafts and as the plow forces the material against the doors they swing open upon their hinges 8 the main 50 portions 24 of the shafts moving in the slots formed by the straps 25 and swinging upwardly and outwardly with the offset portions 26 as their center or fulcrum, see Fig. 4. If the plow presses against the stakes 9 or as the discharging material tends to 55 pack between the plow and the stakes, the latter, by means of the slotted connections 60 between them and the boxes 17^a, move outwardly against the yielding resistance of the springs 17 (see Fig. 5) and so avoid the setting up of a pressure and consequent 65 damage of the stakes. When the crank shaft

is turned to the position shown in Fig. 4, the doors are positively held in their open position.

The movement of the doors as they swing upon their hinges is determined by the extent of the offset portions 26 and to relieve the pressure at the side of the car when this limit is reached the swinging of the crank shafts is continued in the same direction as the initial movement thereof (see arrow 70 Figs. 1, 4 and 5) with the result that the fulcrum point is transferred to the main portions 24 of the shafts and the offset portions 26 swung up out of engagement with the hooks 21, thus completely releasing the 80 doors. As the offset portions 26 swing up from the hooks they encounter the lips 22 and tilt the spring boxes out of engagement with the stub stakes and so release the pivoted stakes which are then free to swing to 85 their position inclining outwardly from the car, the spring boxes passing through the openings 21^a in the stub stakes. When the boxes 17^a are tilted their inner or open ends swing down until the ends of the springs 90 engage with stops 17^b secured to the stakes 9 below the pivot points of the boxes and this position of the boxes is yieldingly maintained by the springs which expand as the boxes swing down and the pins 18 being at 95 this time near the closed end of the boxes also tend to hold the boxes tilted. The boxes are returned to their locking position by inserting the crank-shaft portion in the flared 100 openings presented by the curved hooks 21 and lips 22.

As seen at the left of Fig. 1, when the stakes 9 swing out they carry the top rails and doors with them, the doors in addition to the stakes, assuming an outwardly inclined position with relation to the car. The car side being thus moved to an outwardly inclined position presents an unusually large discharge opening, the hinge points 8 of the doors having been carried bodily to a point 105 110 spaced out from the car, enabling the doors to swing farther away from the car than heretofore. In addition to this the normal capacity of the car is increased at the discharging period and the material loosened 115 and consequently the plowing off of the same more easily performed.

Formerly, in the ordinary type of car, when plowing off to one side only, a space was left between the closed side of the car 120 and the plow 30 as indicated by dotted lines Fig. 1 and, as above described, boulders and the like, instead of being discharged, frequently lodged in this space and as the plow moved forward were jammed against the 125 closed side of the car and damaged the latter. The possibility of damage occurring in this manner is prevented by inclining the pivoted stakes inwardly, as described, so that they assume a position closely adjacent 130

to the plow and bodily shift the top rails and doors so that they also assume such a position and do away with the space at the side of the plow, as indicated at the right of Fig. 1. The springs 17 yieldingly maintain the inwardly inclined position of the stakes and through them that of the top rails and doors so that they are held close to the plow in the event of the latter moving laterally of the car.

As described and indicated by the drawings the sides of the car, including the stakes, are adapted to swing or be adjusted from a position overhanging the car floor, across the pivot point of the stakes 9, to a position inclining out from the car under-structure and flooring, these sides being also permitted a vertical movement and by so constructing the car sides damage is prevented as such sides are permitted to yield under the pressure set up during the plowing off operation instead of resisting such pressure as formerly. Furthermore the retardation of the discharging material is greatly reduced by the enlarged discharge spaces resulting from the swinging of the top rails, the doors and their hinge points bodily outwardly from the car sides.

What I claim is as follows:

- 30 1. A car, the sides of which are yieldingly held in an inwardly inclined position with relation to the car.
2. A car adapted to have a plow passed therethrough and having swinging sides adapted to assume an inwardly inclined position with relation to the car.
3. An open ended car having inwardly inclined sides.
4. A car having an inwardly inclined side adapted to be moved to an outwardly inclined position with relation to the car.
5. In a car adapted to have a plow passed therethrough and having a yielding side including stakes and doors hinged between the stakes, such side being adapted to be moved by the plow.
6. A ballast car adapted to have a plow passed therethrough and having a laterally adjustable side.
- 50 7. In a car, the combination with hinged side doors, of means for controlling such doors including a crank shaft having a shifting fulcrum.
8. In a car, the combination with pivoted stakes and doors hinged between the stakes, of means for controlling the stakes and doors.
9. In a car, the combination with pivoted stakes and doors hinged between the stakes, of retaining means adapted to release the doors independently of the stakes.
- 60 10. In a car, the combination with a stub stake secured to the car, of a stake pivoted to the stub stake and adapted to swing outwardly from the car.
- 65 11. In a car, the combination with a stake pivoted between its ends to the car and a stop adapted to be at all times in the lateral path of the lower portion of the pivoted stake to limit the movement of the latter.

12. A car having a stake adapted to swing from an inwardly inclined position to an outwardly inclined position with relation to the car and a stop adapted to be engaged by the stake in each position.

13. In a car, the combination with the side sill, of a stub stake secured to the side sill, lateral flanges upon the outer side of the stub stake and spaced from the side sill and a stake pivoted between its ends to the stub stake, the lower portion of the pivoted stake being located between the flanges and the side sill.

14. In a car, the combination with pivoted stakes, of stub stakes located intermediate of the pivoted stakes.

15. A car having a stake pivoted to the car and adapted to swing outwardly from the latter and yieldingly held against such movement.

16. In a car, the combination with pivoted side stakes adapted to swing outwardly from the car and hinged doors supported by such side stakes, of means for fastening the stakes and doors, such means being adapted to be operated to successively release the doors and stakes.

17. In a car, the combination with a stub stake and a stake pivoted to the stub stake and adapted to swing outwardly from the car, of a spring located between the stub stake and pivoted stake to yieldingly resist the movement of the latter, a stop for limiting the movement of the stake against the spring and means for removing the stop and the spring.

18. In a car, a stub stake and a stake pivoted to the stub stake to swing outwardly from the car, such stub stake being adapted to form an abutment for the pivoted stake.

19. A car having swinging sides adapted to assume an inwardly inclined position with relation to the car and including hinged doors.

20. In a car, the combination with pivoted stakes and doors hinged between the stakes, of retaining means for the stakes and doors including a crank shaft having two distinct fulcrum points.

21. In a car, the combination of pivoted stakes and doors hinged between the stakes.

22. In a car, the combination with pivoted stakes and doors hinged between the stakes, of means for locking the stakes.

23. A car having stakes and doors hinged between the stakes, such stakes being adapted to swing to an outwardly inclined position with respect to the car body.

24. A car having a stake adapted to swing from an inwardly inclined position to an

70

125

130

outwardly and upwardly inclined position with respect to the car.

25. In a car, the combination with stakes pivoted to the car, of supporting means carried by the stakes and a door hinged to said means.

26. In a car, the combination with side stakes, a top rail upon such side stakes and swinging doors, of means for permitting an upward movement of the stakes, top rail and doors.

27. In a car, a stake pivoted between its ends to swing transversely to the car and a stop at either side of the lower end of the stake, the upper end of said stake being permanently disposed above floor level of the car.

28. In a car, the combination with the side sill, of a stub stake secured to the side sill, extending a short distance above the side sill and being beveled on its inner face, lateral flanges upon the outer side of the stub stake and spaced from the side sill and a stake of channel cross-section pivoted between its ends to the stub stake and adapted to bear against the beveled face of the stub stake, the lower portion of the pivoted stake being located between the side sill and the flanges of the stub stake.

30. 29. In a car, the combination with a stub stake, of a stake pivoted to the stub stake and a spring located between the two stakes.

30. In a car, the combination with two-part stakes, each including a stub stake and a stake pivoted to the stub stake and adapted to swing outwardly from the car and hinged doors supported by the pivoted stakes, of a movable stop between each of

the stub stakes and pivoted stakes and means for holding the doors closed and adapted to 40 be operated to successively release the doors and remove the stops between the stub stakes and pivoted stakes.

31. In a car the combination with a stub stake and a stake of channel cross-section 45 inclosing the stub stake and pivoted thereto, of a box pivoted between the sides of the pivoted stake and bearing at one end against the stub stake, a spring protruding at the opposite end of a box and bearing against 50 the pivoted stake and means for tilting said box out of bearing position with the stub stake.

32. In a car, the combination with stub stakes, a stake of channel cross-section inclosing each stub stake and pivoted thereto and hinged doors supported by the pivoted stakes and presenting slots, of a box pivoted between the sides of each pivoted stake and bearing at one end against the stub 60 stake, a hook at such end of the box, a lip upon the box above the hook, a spring protruding at the opposite end of the box and bearing against the pivoted stake and a 65 crank shaft at the outside of the doors and located in said slots, the offset portions of such shaft being located in the hooks of said boxes.

In testimony whereof, I have signed my 70 name to this specification, in the presence of two subscribing witnesses.

WINFIELD HANCOCK YOST.
